UNITED STATES PATENT OFFICE.

MAURICE J. WRIGHT, OF BOISE, IDAHO.

DESIGN FOR AN ASH TRAY.

Application filed April 14, 1923. Serial No. 5,822. Term of patent 14 years.

To all whom it may concern:

Be it known that I, MAURICE J. WRIGHT, a citizen of the United States, residing at Boise, in the county of Ada and State of Idaho, have invented a new, original, and ornamental Design for an Ash Tray, of which the following is a specification, reference being had to the accompanying drawing, forming part thereof.

The figure is a view in perspective of an ash tray, showing my new design.

I claim:

The ornamental design for an ash tray.

MAURICE J. WRIGHT.
